O. FICHTENBAUM.
CONVERTIBLE SOFA.
APPLICATION FILED MAY 16, 1917.

1,290,152.

Patented Jan. 7, 1919.

Inventor
Oscar Fichtenbaum,
By his Attorney, Geo. A. Byrne.

UNITED STATES PATENT OFFICE.

OSCAR FICHTENBAUM, OF BROOKLYN, NEW YORK.

CONVERTIBLE SOFA.

1,290,152.

Specification of Letters Patent.

Patented Jan. 7, 1919.

Application filed May 16, 1917. Serial No. 168,935.

To all whom it may concern:

Be it known that I, OSCAR FICHTENBAUM, a citizen of the United States, and resident of Brooklyn, in the county of Kings and State of New York, have invented certain new and useful Improvements in Convertible Sofas, of which the following is a specification.

This invention relates to convertible sofas, 10 and has for its general object to provide an improved locking means for securing sections of the bed together and which may be automatically actuated during the operation of converting the device from a sofa into a 15 bed, or vice versa.

To these ends the invention further consists in the novel details of construction and combination of parts more fully hereinafter described and particularly pointed out in 20 the claims.

Referring to the drawings forming a part of this specification, in which like numerals designate like parts in all the views—

Figure 1 is a vertical longitudinal sectional view showing the sections of the bed frame unfolded.

Fig. 2 is a detailed side elevational view of a portion of the frame, showing the mechanism for locking the movable sections one to 30 the other when these are folded, and Fig. 3 is a detailed perspective view of a portion of the frame sections.

The convertible sofa herein shown is an improvement over that disclosed by my co-pending application, filed June 22nd, 1916, Serial No. 105,118. This embodiment comprises the usual housing "a" and the sectional bed frame "b" which may be folded and disposed wholly within the housing "a", 40 in which position of adjustment the frame supports the seat 5. The back 6 is pivotally connected as indicated at 7 to the upper ends of the housing, only one of which is shown, and is arranged to be swung upwardly and 45 rearwardly and to be held in its upper position by means of the latch bar 8 engaging the keeper 9.

The frame "b" consists of a stationary section 10, an intermediate section 11, and an 50 end section 12. The stationary section 10 is rigidly secured to the housing "a" between the ends thereof and is herein shown as being formed of angle iron, and carries at its outer corner portions the uprights 13 and 14. 55 The side rails, one of which is shown at 15, of the intermediate section 11, are pivotally

connected as at 16 to the upper end of the uprights 14, and link connections, one of which is shown and indicated by 17, are made between the adjacent ends of the side 60 rails 15 and the side rails 18 of the end section 12.

The section 12 is made shorter in length than the section 11, and the link connections 65 17 are so proportioned in length as to correspond approximately to twice the thickness of the mattress, so that when section 12 is folded onto section 11 the rails 18 of the former will be parallel to the rails 15 of the latter, as shown by dotted lines in Fig. 1. 70 When the section 12 is folded onto the section 11, as just described, the uprights 18' positioned at the ends of the foot-rail 19 bear on the rails 15 of section 11, in the notched portions 20, as shown.

The length of the section 11 is greater than the corresponding dimensions of section 10, so that when the sections are folded to form 80 a sofa, the ends of the side rails 15 will bear on the upper end of the notched or cut-away portion 21 of the uprights 13 of the stationary section 10.

The seat 5 by means of the links 22 and 23 is pivotally connected to the side rails of the intermediate section 11, and the seat is arranged to move relatively to said section during the initial movement thereof and to be held suspended therebeneath when the section is unfolded.

In folding sections 11 and 12 onto section 90 10, as shown by dotted lines in Fig. 1, slideable latch bolts, one of which is shown and indicated by 24, on the side rails 15, are arranged to engage with the uprights 18'.

This engagement between the latches and 95 uprights has the effect of locking the sections 11 and 12 one to the other, as these move toward section 10. The latch bolts are held against detachment from the rails 15, by pins 25, which pass through slots 26 in 100 said rails, and by means of pivoted links 27 connecting the latch bolts with the links 22 for connecting the seat to the section 11, the latch bolts are automatically brought into and out of engagement with the uprights 18' 105 when the sections 11 and 12 are unfolded or folded onto the section 10.

One end of the spring 28 is connected to the footrail 19 and the opposite end of said spring is connected to a head rail 29. A 110 pair of arms, one of which is shown at 30, are connected to the head rail 29 and are

pivotedly connected as indicated at 31 to a pair of rods, one of which is shown at 32, secured to the frame 10. When the sections 10, 11 and 12 are folded one upon the other, 5 the head rail 29 bears on the portion 29' of the frame 10, but, when the said sections are unfolded the head rail 29 is elevated into the plane of the rails 15 and 18. The elevation of the head rail is caused by the movement 10 of the unfolding of the sections when the device is opened to form a bed. A pair of chains, one of which is shown and indicated by 33, prevent upward movement of the head rail beyond the position just stated. 15 When the sections are folded one upon the other, the spring 28 is relaxed, but the unfolding of the section 12 operates to tension said spring, due to the fact that the chains 33 operate to hold the head rail 29 against 20 upward and outward movement during outward and downward movement necessary to adjust section 12 into horizontal alinement with section 11.

With respect to the position of the parts 25 as indicated at Fig. 1, it will be observed that the outer end portions of the rails 11 are provided with rigidly attached supports, one of which is shown at 34. The ends of these supports come into contact with the 30 floor and operate to support the section 11, when the same is unfolded, and link connections, one of which is shown at 35, extend between the lower ends of the supports 34 and the supports, one of which is shown 35 at 38 of section 12. The supports 36 are pivotally connected to the rails 18 and the links operate to fold and unfold said supports during the folding and unfolding of the section 12. When the section 12 is unfolded, 40 the links 35 coöperate with the supports 34 and 36 to provide a support common to the sections 11 and 12.

When the parts are in the folded position, the device is used as a sofa, and it may be 45 converted into a bed by causing the said back to move upwardly and outwardly until the latch bar 8 engages with the keeper 9. In this position of adjustment of the back, a sufficient space is afforded to permit the 50 operator on taking hold of a convenient portion of the section 11 to unfold the same

and section 13 to the position shown by dotted lines in Fig. 1. During the unfolding of the sections, as just described, the latch bolts are disengaged from the uprights 18", so that the end section may be unfolded and the device converted into a bed. In converting the device into a sofa, section 12 is folded onto section 11 and the said sections 11 and 12 are then folded onto section 10, and the back 6 is then permitted to descend to engage the upper face of the rear end portion of the seat, after first disengaging the latch bar 8 from the keeper 9. 55

It is obvious that those skilled in the art 60 may vary the details of construction and arrangement of parts without departing from the spirit of my invention and, therefore, I do not wish to be limited to such features except as may be required by the 65 claims.

What I claim is—

1. In a combined bed and sofa, the combination of a sectional folding bed frame, including a stationary section, an intermediate section and an end section, a movable seat mounted on said frame, uprights mounted on said end section and adapted to engage the intermediate section for holding said sections in spaced relation when folded, 75 latches mounted on the intermediate section adapted to engage the uprights and to be actuated by said seat for locking said intermediate and end sections one to the other when the frame is being folded. 80

2. In a combined bed and sofa, the combination of a sectional folding bed frame, including a stationary section, an intermediate section, and an end section, a movable seat mounted on said frame, uprights mounted on said end section, and automatic locking means positioned at the sides of the intermediate section and adapted to engage the uprights and to be actuated by the seat for locking said intermediate and end sections one to the other when the frame is being folded. 90

Signed at New York, in the county of New York and State of New York this 12th day of May A. D. 1917.

OSCAR FICHTENBAUM.
